Herman Mockus
INVENTOR

BY Victor J. Evans

WITNESS:

ATTORNEY

UNITED STATES PATENT OFFICE.

HERMAN MOCKUS, OF CHICAGO, ILLINOIS.

DRAINAGE VALVE.

Application filed March 18, 1925. Serial No. 16,496.

To all whom it may concern:

Be it known that I, HERMAN MOCKUS, a citizen of the United States, residing at Chicago, in the county of Cook and State of Illinois, have invented new and useful Improvements in Drainage Valves, of which the following is a specification.

This invention relates to new and useful improvements in drainage valves and more particularly to a device of this character which is applicable to drainage openings and the like which are usually placed in the floors of basements, cellars, etc.

The main object of my invention is the provision of a drainage valve whereby the same is so constructed as to be readily applied to the usual drainage openings in basements and is normally in a closed position to prevent any backing of water from the sewer from entering the basement and which can be quickly and readily actuated when it is desired to drain any water from the basement floor.

Another object of my invention is the provision of a drainage valve including suitable means for normally retaining the valve in a closed position with additional means whereby the same may be manually manipulated for operating the valve to permit drainage thru the drain pipe to which the valve is attached.

A further object of my invention is the provision of a drainage valve wherein the operating parts thereof are within the usual concrete flooring in basements and the like so as to prevent articles from being brought into contact with the working parts whereby the valve will be ready for operation at all times.

With the above and other objects in view, the invention consists in the novel features of construction, the combination and arrangement of parts hereinafter more fully set forth, pointed out in the claims and shown in the accompanying drawings, in which:

Fig. 1 is a top plan view of the drainage valve constructed in accordance with my invention, parts thereof being broken away and illustrated in section,

Fig. 2 is a longitudinal sectional view, and

Fig. 3 is a detail transverse section on the line 3—3 of Fig. 1.

Referring more particularly to the drawings, the numeral 1 indicates a drainage pipe leading to well-known drainage system

and attached to the upper end of this pipe is a catch basin 2, having a perforated plate 3 arranged horizontally against the basement adjacent the upper end thereof. This basin is usually set into the concrete flooring 4 of a basement and generally at a low spot whereby any water on the floor of the basement will readily run toward the base 2. As this catch basin 2 normally remains in an open position, the water from the sewer has a tendency to back thru the same into the basement of the building and in order to prevent this backing of the water, I have constructed a novel form of valve which normally closes the communication to the sewer and prevents any backing of water therein.

Suitable housings 5 and 6 are arranged adjacent the basin 2, said housings being preferably in spaced relation as shown in Fig. 2 and connecting the housings is a sleeve 7.

Movable thru the housings 5 and 6 and the sleeve 7 is an operating shaft 8, the inner end of which is connected as at 9 to a perforated valve plate 10. The plate 10 is mounted within the suitable opposed guides 11 connected to opposite sides of the basin 2.

The shaft 8 is provided adjacent its inner end with a head 12 which normally bears against a shoulder 13 in the housing 5. Disposed between the head 12 and the outer wall of the basin 2 is a coil spring 14 which normally retains the shaft 8 in an outward position with the head 12, bearing against a shoulder 13. This position retains the perforations in the valve plate 10 out of alignment with the perforations in the plate 3.

The housing 6 has extended outwardly therefrom a shaft 15, having a hand wheel 16 upon its outer end and a crank arm 17 at its inner end which is arranged within the housing. The crank arm 17 is connected to the outer end of the shaft 8 by means of a link 18 whereby it will be noted that when the shaft 15 is rotated, turning the handle wheel 16 to the right, the shaft 8 will be reciprocated inwardly toward the catch basin 2 compressing the spring 14 and moving the valve plate 10 so that the perforations therein will be brought into alignment with the perforations in the plate 3, permitting any water standing above the catch basin to be drained therethru.

In order to provide for proper alignment for the perforations in the plates 3 and 10, a stop pin 19 is carried by the shaft 8 and is adapted to engage with the shoulder 13 5 in order to limit the movement of the shaft 8 upon its inward stroke, thus as the pin 19 strikes the shoulder, the plate 10 will have been moved a sufficient distance to bring the perforations therein into alignment with the 10 perforations in the plate 3.

It will be apparent from the foregoing that when the hand wheel is released after completely draining the water thru the basin, the tension of the spring 14 will return the 15 shaft 8 to its normal position, closing the openings between the plates 3 and 10 whereby the drainage valve will always remain in a normally closed position to prevent any 20 backing of the water from the sewer thru the drain into the building.

As noted the several parts of the device are embedded or arranged beneath the surface of the cement floor whereby they will be entirely out of the way and the hand 25 wheel 16 may be located at one side of the basement and the shaft 8 connected thereto in any suitable manner.

While I have shown and described the preferred embodiment of my invention, it will 30 be understood that various changes and alterations may be made without departing from the spirit of the invention or the scope of the appended claims.

Having thus described my invention, what 35 I claim is:

1. In combination with a catch basin having a stationary perforated plate therein, a movable perforated plate upon one side of the stationary plate, a housing adjacent the

basin, a shaft mounted for reciprocating movement thru the housing and having its inner end attached to the movable plate, a stop shoulder within said housing, a head on the rod, a coil spring on the rod disposed between the head and one wall of the basin for retaining the head against said shoulder and manually operated means for imparting movement to the shaft against the tension of said spring to align the openings in the plate with the openings in the stationary 40 plate.

2. The combination with a drain opening having a perforated plate against the same, of a movable valve plate disposed beneath the first plate and having openings therethru, a longitudinally movable shaft having one end connected to the valve plate, manually operated means connected to the other end of the shaft, a head portion on the shaft, a spring normally bearing against the head for moving the shaft in one direction, a stop shoulder adapted to be engaged by the head to limit the movement of the shaft, a pin carried by the shaft in spaced relation with the head for engaging the stop shoulder upon the opposite side to limit the movement of the shaft in the opposite direction whereby the openings in the valve plate may be aligned with the perforations in the drain plate against the tension of the spring thru the manually operated means and the tension of said spring reciprocating the shaft in the opposite direction to move the openings in the valve plate out of alignment with the openings in the drain plate.

In testimony whereof I affix my signature.

HERMAN MOCKUS.
